1972, Ser. No. 291,774

Term of patent 14 years

Int. Cl. D22—05

U.S. Cl. D22—26

FIG. 1 is a top plan view of a combination ice fishing reel handle and jig stick embodying our new design;

FIG. 2 is a side elevational view thereof;

FIG. 3 is a bottom plan view thereof;

FIG. 4 is a side elevational view thereof from a side opposite from FIG. 2;

FIG. 5 is a sectional view thereof taken on line 5-5 in FIG. 2;

FIG. 6 is an end view thereof looking at the handle end;

FIG. 7 is an end view thereof looking at the opposite end from FIG. 6; and

FIG. 8 is a view of a reel handle portion thereof with the jig stick removed, the features of reel handle being identical to that portion thereof in the previous figures.

This application is a continuation-in-part of our co-pending design patent application Ser. No. 180,245, filed

Sept. 13, 1971, for Ice Fishing Jig Stick and Reel, now abandoned.

We claim:

The ornamental design for a combination ice fishing reel handle and jig stick, as shown and described.
